UNITED STATES PATENT OFFICE.

NEILS A. NEILSEN, OF CUPERTINO, CALIFORNIA.

GAP-CLOSING MACHINE.

1,399,981.

Specification of Letters Patent. Patented Dec. 13, 1921.

Application filed June 28, 1920. Serial No. 392,315.

To all whom it may concern:

Be it known that I, NEILS A. NEILSEN, a citizen of the United States, and resident of Cupertino, in the county of Santa Clara and State of California, have invented certain new and useful Improvements in Gap-Closing Machines, of which the following is a specification.

My invention relates to a machine particularly adapted for filling gaps in earth ridges formed for irrigating purposes.

It is the object of my invention to provide a device of the character indicated in which a scoop is provided with a pivoted bottom normally locked in position but easily unlocked by manipulating the handles of the device. It is a further object of my invention to utilize the draft mechanism of the device as a partial means of effecting the unlocking of the same, and means coöperating with the same for automatically locking the pivoted bottom after a dumping operation.

In the drawing:—

Figure 1 is a plan view of my invention. Fig. 2 is a section on line 2—2 of Fig. 1.

Fig. 3 is a rear elevation of my invention.

Fig. 4 is a detail of a portion of the bottom locking and tripping mechanism in operative position with relation to the draft mechanism.

Fig. 5 is a diagrammatical illustration of a portion of intersecting ridges showing gaps to be closed.

Fig. 6 is a diagrammatical illustration showing the operation of the device.

Referring more particularly to the drawing, 1—1 indicates the two sides of the device, and 2 indicates the back of the same, 40 of suitable size and form and secured at the back corners by angle irons 3 and tied at the front by bar 4. Sides 1—1 are provided with handles 5—5 and a draw bar 6 pivoted thereto by means of plates 7—7, the bar 45 6 having an upwardly extending rod 8 positioned at its center and provided with an eye 9 to engage end 10 of rod 11 passing rearwardly of the device for the purpose hereinafter described.

At a central point in the lower edges of sides 1—1 is pivoted a bottom 12 by means 50 of pivots 13, bottom 12 being normally held in the position shown by pins 14 extending through the openings 15 in the sides 1 just above the bottom 12 and forward of pivots

13 and carried on the lower ends of springs 16 secured to sides 1. A third pin is shown at 17 extending through orifice 18 in the back 2 and just above the rear end of bottom 12. This pin 17 is carried by bar 19 60 provided with a shoulder at 20 and pivoted at 21 to a bracket 22 mounted on back 2 of the device.

A bar is shown at 23 pivoted at 24 to the upper end of bracket 22 and pivoted at its 65 lower end to the upper end of bar 19 as shown at 25. A spring 26 is inserted back of this joint and mounted on back 2 as shown. The upper end of bar 23 is provided with an eye 27 to engage rod 11 on which it 70 is held by means of nut 28. An adjustable stop is shown at 29 slidably mounted on rod 11 and fastened by set screw 30. The spring 26 serves to normally hold pin 17 75 extending through orifice 18 so as to engage the rear edge of bottom 12, thereby normally locking bottom 12 in the position shown during the advance of the device.

In use there is a steady pull upon bar 6, therefore it maintains a very constant position with relation to the rest of the device, and the nut 28 is positioned so as to contact with eye 27 of rod 23 thereby normally holding the pin 17 in an operative position. Stop 29 is positioned slightly 85 in front of eye 27 so that when the device as a whole is tilted upwardly a little way by means of handles 5 the end 27 of bar 23 is thrown forwardly against the said stop 29 thereby causing the bars 19 and 23 90 to bend in against spring 26 at joint 25 and causing the withdrawal of pin 17 as shown in Fig. 4.

It is clear of course that stop 29 must be 95 adjusted according to the height of draw bar 6, since if the bar 6 is connected say to a tractor and is raised then stop 29 must be moved forward a distance, but the same relative distance between stop 29 and eye 27 must be maintained.

In irrigating orchards by the check or flooding system, a suitable implement is used to throw up a series of parallel ridges extending from one side of the orchard to the other. To form the squares or basins 105 to receive the water it is necessary to form another series of parallel ridges extending at right angles to the first series. In doing this, however, the ridging machine necessarily cuts through the ridges first formed 110

thereby forming gaps therein as at 31, the numeral 32 indicating one of the first formed ridges, and 33 one of the ridges formed afterward and crosswise of the first.

5 To close these gaps so that each check or square will retain the water turned therein is a great task when done by hand on an orchard of many acres as it is customary to form a square of ridged land about every 10 tree. By means of the device herein described the labor is reduced to a minimum and the gaps are quickly filled with but little effort on the part of the single operator of the machine as he has merely to lift 15 upwardly a little on handles 5 to effect the withdrawal of pin 17 as described. Upon withdrawing pin 17 the forward edge of bottom 1 engages the ground and the whole structure moves forward over the earth 20 dumped by the turning of bottom 12 as shown in Fig. 6, the said bottom 12 making a complete half turn to be stopped by pin 17 to pick up a new load.

In the present case pins 14 are rounded 25 upon their upper edges to permit bottom 12 to slide easily thereover, but are flat on their under sides to squarely engage the said bottom 12 and prevent its rotation in the wrong direction.

30 It is to be understood of course that changes in details of construction and method of operation may be made within the scope of the appended claims.

I claim:—

1. A gap closing machine comprising a 35 scraper body, a revoluble bottom mounted thereon, a draw-bar attached thereto, a rod mounted on said draw-bar and extending rearwardly of said body, a bar pivotally mounted on said body, a pin carried thereby and normally engaging said bottom, a link pivotally mounted on said body and pivotally connected to said bar at one end and engaging said rod at the other end, and a stop on said rod arranged to contact with 40 said link when said body is tilted and operate said bar to remove said pin from engagement with said bottom.

2. A gap closing machine comprising a 45 scraper body, a revoluble bottom mounted thereon, a draw-bar attached thereto, a rod mounted on said draw-bar and extending rearwardly of said body, a bar pivotally mounted on said body, a pin carried thereby and normally engaging said bottom, a 50 link pivotally mounted on said body and pivotally connected to said bar at one end and engaging said rod at the other end, and a stop on said rod arranged to contact with 55 said link when said body is tilted and operate said bar to remove said pin from engagement with said bottom, and resilient means for maintaining said pin in an operative position with relation to said bottom when said body is in a normal position. 60
